UNITED STATES PATENT OFFICE.

FRANK B. ANDERSON, OF CLEVELAND, OHIO, ASSIGNOR TO THE V. D. ANDERSON COMPANY, OF CLEVELAND, OHIO, A CORPORATION OF OHIO.

TEMPERING APPARATUS FOR OIL-BEARING MATERIALS.

Application filed July 26, 1922. Serial No. 577,710.

This invention pertains to a moisture feeding device for tempering apparatus, and more specifically to means employed to feed the required amount of water to material 5 which is passed into and through a tempering apparatus and therein treated preparatory to its being fed to a suitable expressing apparatus or press wherein it is subjected to an expressing action to remove the oil and 10 moisture content.

In the treatment of certain materials for the purpose of expressing oil or grease therefrom, it is essential that the material contain moisture, for otherwise the material will 15 not give up the oil as freely as desired and the cake which passes from the apparatus will not be oil free or substantially so.

The apparatus is especially designed to be used in conjunction with the so-called Anderson expeller, as depicted in Letters Patent 829,315, Anderson, dated August 21, 1906, though, of course, its use is not limited to such a type of press.

A simple embodiment of the invention is 25 shown in the accompanying drawings wherein,

Fig. 1 is an end elevation, partly in section, of the combined water feeding mechanism and tempering apparatus;

Fig. 2 a side elevation thereof, the parts 30 broken away so as to more clearly show the construction;

Fig. 3 a top plan view of the trough from which the water is removed in measured 35 quantities and fed to the tempering device;

Fig. 4 a vertical sectional view thereof, taken on the line IV—IV of Fig. 3;

Fig. 5 a vertical sectional view of the water 40 trough, the measuring wheel and its allied parts, the section being taken on the line V—V of Fig. 1; and

Fig. 6 a similar view taken on the line VI—VI of Fig. 5.

In the drawings, 1 indicates so much of a 45 tempering apparatus as is necessary to an understanding of the invention, said apparatus having, as illustrated, the form of a trough provided with an exteriorly located jacket 2 between which and the body of the trough, steam is interposed for the purpose of heating the same. Extending through the trough is a shaft 3, upon which is mounted a series of interconnected collars or sleeves 4 carrying stirring or propeller blades 5 which agitate the material and tend

to feed it from the intake end, which is that portion which is illustrated, toward the discharge end and into a press such as is shown in the Anderson patent above referred to, or to any other suitable expressing means.

Secured to the frame of the tempering apparatus is an upwardly extending bracket 6 which forms the support for a water reservoir or chamber indicated generally by the numeral 7. Said reservoir is open at its upper side, and is provided with a longitudinally extending upstanding partition or wall 8, and two transversely extending short walls or dams 9 and 10. There is thus produced

within the reservoir by said walls or partitions just referred to, and the outer walls of the reservoir proper, a main water supply chamber 11, a second chamber 12, into which the measured quantity of water is deposited by the water wheel hereinafter referred to, a discharge chamber 13, which is in communication with the tempering apparatus as herein set forth, and an overflow or outlet chamber 14 for any excess of water.

A supply pipe 15 (Figs. 1 and 6) opens into the upper portion of the main water supply chamber 11, and the water is maintained in said chamber at a predetermined height by the dam 10, any excess flowing over the dam

and down through the short pipe or nipple 16 which terminates in the upper portion of a sight discharge casting 17, from which leads a pipe 18 to the sewer or a reservoir in which the excess water may be collected.

The said discharge casting, as will be best seen upon reference to Figs. 2 and 6, is open at one side so that the attendant may see that the proper amount of water is within the main water supply chamber 11, this being determined by the passage of the water from

the lower end of the nipple 16 and the dropping thereof through space into the lower portion of the casting 17.

The water in measured quantities is deposited into the chamber or trough 12 in a manner shortly to be described, and passes over the dam 9, which is lower than the longitudinal partition 8, into the discharge chamber 13, through the nipple 19 which is in communication with the lower portion of

said chamber 13, said nipple terminating in the upper portion of a sight feed casting 20 (see Fig. 2) which is open at one side so that the operator may, when standing on the floor, readily determine if the proper

feed is being effected. A pipe 21 opens from the lower portion of this sight feed device 20 and conveys the water into the upper portion of the tempering apparatus 1.

5   Mounted within a bearing 22 formed upon the upper portion of the outer wall of the reservoir 7, is a shaft 23. To the inner end of the shaft there is secured a measuring device for the water, comprising a wheel 10 having a series of pockets or buckets 24 equally spaced about its axis, each bucket having a mouth 25 at the outer end thereof, which, as the wheel is rotated, dips into the water in the main water supply chamber 11, 15 each bucket likewise having an opening, as 26 (see Fig. 5) at the inner portion thereof, the inner wall of the mouth of each bucket forming a part of a frustro-conical hub extension 27. Secured to the outer face of the 20 wheel is a funnel shaped delivering element 28 having a central cone 29, the base of which abuts the outer end of the hub section 27 so that said elements 27 and 29 form, in effect, a cone, and the openings 26 extending 25 from the pockets likewise communicate with passages formed in the funnel shaped member 28 by ribs or partitions 30 extending radially therein, so that the water which is picked up by each of the pockets will be 30 discharged when that particular pocket reaches its uppermost position, and will pass therefrom into the measuring chamber 12 and thence over the dam 9 down through the sight feed member 20 and through the pipe 35 21 to the tempering apparatus.

It is designed to have the water wheel work in timed relation with the paddle mechanism or other feeding device located within the tempering apparatus, and to this 40 end the following mechanism may be employed:

Secured to the outer end of the shaft 23 is a gear 31 which in turn meshes with a pinion 32 shown as formed upon the outer 45 end of a stub shaft 33, the latter being supported in a bearing 34 formed as a part of the reservoir 7. The shaft 33 has swiveled thereon a rocker element comprising a hub 35, from which there extends upwardly an 50 arm 36 to which is pivoted a pawl 37 adapted to engage the teeth of a ratchet wheel 38 secured to the shaft 33. A downwardly extending lug or extension 39 is formed integral with the hub 35 and a rod or arm 40 55 is securely fastened therein and extends outwardly and downwardly therefrom. Secured to a bracket 41 extending downwardly from the bearing 34, is a gravitating locking pawl 42 which engages the ratchet wheel 38 and prevents retrograde movement thereof. Secured to the outer end of the shaft 3 is a crank 43, the pin 44 whereof is connected to one end of a pitman 45, the other end of which is secured to a block 46 60 through which the rod 40 extends. The 65

block 46 is adjustably mounted on the rod 40 and may be moved up and down thereon and held in its adjusted position through a clamping screw 47. Thus by moving the block along the rod and securing it in its 70 adjusted position the rocker carrying the actuating pawl 36 will have imparted thereto a greater or less throw with the consequence that a greater or less number of revolutions will be imparted to the water 75 measuring wheel for each revolution of the shaft 3, so that a greater or less quantity of water will be fed to the tempering apparatus under such conditions. Thus by a simple 80 adjustment of the block 46 with reference to the rod 40, a greater or less amount of water may be accurately fed to the tempering apparatus, according to the needs of the material passing therethrough.

Preferably a cover 48 will be placed over 85 the water wheel and its allied parts, the same being hinged about a bracket 49 provided with an outward extension 50 upon which the cover may come to rest when it is thrown upwardly and to one side. 90

It is thought that the operation of the device is clear from the above description and therefore a detailed exposition of the operation is not deemed necessary. 95

What is claimed is,—

1. In combination with a device for tempering solid materials; means for feeding material therethrough; a water reservoir having a main water supply chamber and a second chamber into which the measured 100 water from the main water supply chamber is deposited; a dam serving to maintain the water level at a fixed point in the supply chamber; a conduit extending from the second chamber and delivering the water into 105 the tempering apparatus; a pocketed measuring wheel mounted above the reservoir, the pockets whereof dip into the main water supply chamber and discharge the water into the second chamber aforesaid; and means for driving said pocketed wheel in timed relation to the feeding means located 110 within the tempering device.

2. In combination with a device for tempering solid materials; means located therein 115 for feeding such material therethrough; a water reservoir; a dam for maintaining a constant water level in the reservoir; a pocketed measuring wheel located above said reservoir and dipping thereinto, said wheel adapted when rotated to pick up and deliver measured quantities of water to the tempering device; and means for effecting an adjustment of the speed of rotation of the measuring wheel with reference to the 125 speed of movement of the feeding means.

3. In combination with an apparatus for tempering solids, means for feeding the solids therethrough, a water supply reservoir comprising a main supply chamber and 130

a second chamber, a dam in each of said chambers dividing each of the latter into liquid holding compartments and overflow compartments respectively, sight-feed outlets connected with each of said overflow compartments, the outlet from the second chamber overflow compartments discharging into the tempering apparatus, a pocketed measuring and liquid feeding wheel mounted above said main supply chamber, the pockets whereof dip into the liquid holding compartment thereof and are constructed with centrally disposed passageways extending into the second compartment, and means for actuating said wheel in timed relation with the feeding means within the tempering apparatus.

In testimony whereof I have signed my name to this specification.

FRANK B. ANDERSON.
